Primary Examiner — Christian P. Mclean

(74) *Attorney, Agent, or Firm* — Grants Law Firm; Allan Grant

(57) **CLAIM**

The ornamental design for a doll hair as shown and described.

DESCRIPTION

FIG. 1 is a front perspective view of the doll hair.
FIG. 2 is the front view of the doll hair.
FIG. 3 is a back view of the doll hair.
FIG. 4 is a side view of the doll hair.
FIG. 5 is the other side view of the doll hair.
FIG. 6 is a top view of the doll hair; and,
FIG. 7 is a perspective view of the doll hair exploded showing the doll hair being attached.
The broken lines illustrating a doll's face show environmental structure that forms no part of the claimed design.

1 Claim, 7 Drawing Sheets
